CLAIM

I claim the ornamental design for a helmet, as shown and described.

DESCRIPTION

FIG. 1 is a perspective view of a helmet showing the new design;

FIG. 2 is a front elevation view of the helmet of FIG. 1;
FIG. 3 is a rear elevation view of the helmet of FIG. 1;
FIG. 4 is a right side elevation view of the helmet of FIG. 1;

FIG. 5 is a left side elevation view of the helmet of FIG. 1;
FIG. 6 is a top plan view of the helmet of FIG. 1; and,
FIG. 7 is a bottom plan view of the helmet of FIG. 1.
The broken lines in the drawings depict portions of the
helmet that form no part of the claimed design.
